CABINET FOR ELECTRONIC EQUIPMENT

Leon Gordon Miller, Shaker Heights, Ohio, assignor to Bud Radio, Incorporated, Willoughby, Ohio

Filed Aug. 28, 1970, Ser. No. 24,751

Term of patent 14 years

Int. Cl. D14—02

U.S. Cl. D26—5

FIG. 1 is a front and top perspective view of a cabinet for electronic equipment showing my new design as seen from the left, a similar perspective view as seen from the right would present a mirror image thereof; and

FIG. 2 is a perspective view thereof showing the rear, bottom and side opposite to that shown in FIG. 1.

I claim:

The ornamental design for a cabinet for electronic equipment, as shown and described.
